UNITED STATES PATENT OFFICE.

GEORGE O. DENISON, OF WATERLOO, INDIANA, ASSIGNOR TO HIMSELF
AND MICHAEL KIPLINGER, OF SAME PLACE.

BAG-HOLDER.

SPECIFICATION forming part of Letters Patent No. 242,282, dated May 31, 1881.

Application filed March 25, 1881. (No model.)

To all whom it may concern:

Be it known that I, GEORGE OSCAR DENISON, of Waterloo, in the county of De Kalb and State of Indiana, have invented a new and Improved Bag-Holder; and I do hereby declare that the following is a full, clear, and exact description of the same, reference being had to the accompanying drawings, forming part of this specification, in which—

10 Figure 1 is a perspective view of my invention, showing a bag attached. Fig. 2 is a top plan view. Fig. 3 is an end view.

15 My invention relates to improvements in bag-holders; and it consists in certain details of construction hereinafter more fully set forth.

20 In the accompanying drawings, *a* represents a bag-holder, preferably oval in horizontal section, and made low in front and high in rear to expedite the filling of the sack and prevent the grain from running out at the rear of the bag-holder. The bag-holder *a* is provided with suitable hooks, *b*, adapted to be inserted into the upper end of the sack to secure it to the bag-holder.

25 *c* is a coiled spring, having its straight ends hooked to engage with eyes *d*, secured to the opposite ends of the major axis of the bag-holder. The coiled spring *c* is preferably formed of one piece of wire, and is provided with a

30 stem, *e*, having an eye, *h*, at its upper end, by which the bag-holder is hung on a nail or pin. The coiled spring thus forms a bail for the bag-holder, by means of which it is suspended. To the rear side of the bag-holder, at its mid-

35 dle, is secured the vertical stay *i*, having an

eye, *j*, at its upper end, through which the stem *e* passes.

By this construction it will be seen that the bag-holder introduced into the mouth of a sack will be prevented from tipping too far forward or backward in filling a sack, and that the bag-holder will be held in a horizontal position, or nearly so, in filling a sack secured thereto.

By suspending the bag-holder from a spring, as above described, the sack secured thereto will drop to the floor when grain is introduced into it, thus relieving the strain on the hooks secured to the sack and preventing the tearing of the same, and the lifting of filled bags to remove them from the hooks is entirely dispensed with, as the bag-holder can be drawn down and the hooks disengaged from a sack without lifting or moving the same.

What I claim as my invention is—

1. The combination, with the bag-holder *a*, provided with the stay *i*, having an eye, *j*, at its upper end, of the coiled spring *c*, pivoted to the bag-holder and provided with the stem *e*, passing through the eye *j*, substantially as described, and for the purpose set forth. 55

2. The combination, with the bag-holder *a*, made low in front and high in rear, and provided with hooks *b*, eyes *d*, and stay *i*, having eye *j*, of the coiled spring *c*, having hooked ends, and stem *e*, having eye *h*, substantially as described, and for the purpose set forth. 65

GEORGE OSCAR DENISON.
